UNITED STATES PATENT OFFICE.

RAY P. SAFFOLD, OF DOUGLAS, ARIZONA.

ORE-SEPARATING APPARATUS.

1,256,263.

Specification of Letters Patent. Patented Feb. 12, 1918.

Application filed July 12, 1915. Serial No. 39,527.

To all whom it may concern:

Be it known that RAY P. SAFFOLD, (whose post-office address is P. O. Box 477,) a citizen of the United States, residing at Douglas, in the county of Cochise and State of Arizona, has invented certain new and useful Improvements in Ore-Separating Apparatus; and I do hereby declare the following to be a full, clear, and exact description of the invention, such as will enable others skilled in the art to which it appertains to make and use the same.

The invention relates to improvements in apparatuses for the recovery or separation of precious metals from their ores, and more particularly to that type of apparatus wherein the ore, in pulpy condition, is subjected to the action of suitable chemicals, while in a state of agitation, and then passed into a selective liquid body where separation obtains, the metal particles or concentrates rising to the upper level of the heavy liquid body and floating or frothing therefrom, while the slimes or tailings pass to the lower level of the latter, the latter being less buoyant, in character, than the metal particles or concentrates for such result.

The primary object of the invention is to provide a comparatively compact, efficient and inexpensive apparatus of this character, and one in which the percentage of resultant values, to be obtained, is greater than is that of such apparatuses, now known.

With this and other objects in view, the invention resides in the certain new construction to be hereinafter more fully described, set forth in the appended claim, and illustrated in the accompanying drawings, in which:

Figure 1 is an elevation of the preferred embodiment of the invention,

Fig. 2 is a top plan view,

Fig. 3 is a vertical section on the line 3—3 of Fig. 2,

Fig. 4 is a transverse section on the line 4—4 of Fig. 3,

Fig. 5 is a vertical section of a modified construction of the same,

Fig. 6 is a top plan of a second modified form thereof,

Fig. 7 is a transverse section on the line 7—7 of Fig. 5,

Fig. 8 is a top plan view showing a modified construction of the agitator casing therefor.

Referring to the accompanying drawing,

in which similar characters of reference designate corresponding parts in the several views, the numeral —1— denotes a slimes or tailings hopper, of any desired shape and size, supported by or within a suitable base —2—, the same comprising, as shown, a cylindrical body provided with a supporting flange —3— to be secured to the hopper —1— by means of rivets or the like —4—. A valved out-let —5— is provided for controlling the discharge of the contents of the hopper —1— and is suitably disposed in the bottom wall —6—, of the latter, suitable openings —7— being formed in the cylindrical body or base —2— for access to the same for its operation. Extending peripherally of the top edge of the hopper —1— is a trough-like member or launder —8—, which may be supported or secured thereon in any desired manner, and the same is arranged to incline downwardly throughout its length and terminate in a plane below its starting point or upper end, which is disposed flush with the edge of the hopper. A depending apron —9— connects the inner wall of the launder —8— with the top edge of the hopper —1— throughout its length to direct the flow of material thereto, during the operation of the apparatus. The lower terminal of the launder —8— is provided with an out-let —10— through which the material passes to a discharge pipe —11—.

A casing —12— is disposed vertically of the hopper —1— and is formed with a flange —13— by means of which it is positioned centrally of the latter and secured to the wall thereof with suitable fastenings —14—. A series of baffle plates —15— are arranged in spaced relation within and secured in proper position to the wall of the casing —12— by means of suitable fastenings —16—, and are each formed with a centrally disposed opening —17—. Equidistantly spaced around the upper edge of the casing —12— are a series of angularly arranged lugs —18— adapted to receive and support thereon similar lugs —19—, of a cover-plate —20—, each coacting pair of lugs —18— and —19— being formed with aligned openings for the reception of suitable fastenings —21—. The casing —12— is formed with a conical-shaped bottom wall —22—, below which and approximately at the juncture of the flange —13— with the casing —12—, the latter is provided with

oppositely disposed slots or openings —23— whereby to establish communication between the upper and lower portions of the hopper —1—. Rising from the cover-plate 5 —20— is a yoke comprising standards —24— and a cross-bar —25—, the latter being formed to provide a shoulder —26—, intermediate its ends, which is, in turn, formed to provide a circular channel or raceway 10 —27— opposed to a similar channel or raceway —28—, formed in a bearing plate —29— and adapted to retain a series of ball-bearings —30— therebetween. The bearing-plate —29— is keyed at the upper end of a 15 vertically disposed shaft —31— which depends from the cross-bar —25— into the casing —12— and rests in a recess —32— formed in the bottom wall —22— for the reception of the lower end thereof. The 20 upper face of the cover-plate —20— is provided with a centrally disposed bearing-shoulder —33—, surrounding an intermediate portion of the shaft —31—, and is formed with a circular channel or raceway 25 —34— adapted to retain a series of ball-bearings —35— which are also engaged in a second channel —36—, opposed to the channel —34—, of the bearing-plate —37— carried by and keyed to the shaft —31—. 30 Adjacent the upper end of the shaft —31—, at a point thereon intermediate the cross-bar —25— and the upper face of the cover-plate —20—, is arranged and keyed a pulley —38— by means of which power is to be 35 applied for the rotation of the shaft. Spaced along the length of the shaft —31—, between the cover-plate —20— and the bottom wall —22—, and keyed thereto, are a series of agitator plates or disks —39—, 40 which are arranged each between oppositely disposed baffle-plates —15—, and which are of a diameter sufficient to extend for a distance beyond the periphery of the oppositely disposed openings of the baffle-plates. The 45 lower agitator disk —40—, however, is provided, on its under face, with a series of radially disposed ribs —41—, which are inclined rearwardly to conform to the inclination of the bottom wall adjacent thereto. A 50 series of slots or openings —42— are provided in the wall of the casing —12— and are disposed substantially in the plane of the lower disk —40—. For admitting the pulp, or other material to be treated, the 55 cover-plate —20— is formed with an opening or inlet —43— above which is arranged a funnel or hopper —44— secured to the cover-plate by means of suitable fastenings. Referring more particularly to the modified form of the invention, as shown in Figs. 60 5, 6 and 7, the numeral 50 denotes a slimes or tailings hopper, preferably made square to provide an inverted frusto-pyramidal shaped body, or the same may be frusto-65 conical if desired, supported upon a sub-

hopper —51—, and secured thereto by means of rivets or bolts —52—. Rising centrally of the tailings hopper —50—, is an agitating chamber or casing —53—, formed with or secured at the lower edges of the walls of 70 the hopper, and having its upper end projected slightly above the top edge of the latter, which upper end of said casing —53— is provided with an angularly disposed flange —54— to which is to be secured, by 75 means of bolts —55—, a cover-plate —56—. Rising centrally of the cover-plate —56— is a feed-hopper —57— opening into the agitating chamber, and having its upper end flared as at —58—. The casing —53— is 80 formed with sets of openings or discharge ports —59— and —60—, the former being disposed in a plane slightly below the upper edge of the hopper —50—, and the latter in a plane slightly above the bottom of the casing. Depending centrally of the feed-hopper —57— and the casing —53— is a pressure pipe —61— having its lower end connected with a multiport coupling —62—, supported upon the bottom wall of the casing 85 immediately below the discharge ports —60—, and provided with radially projecting, upwardly discharging, nozzles, —63—, one for each port of said coupling. A series of openings —64— are provided in a connecting wall —65— between the lower end of the hopper —50— and the casing —53— to establish communication between the hopper —50— and the sub hopper —51—. The lower wall of the sub-hopper —51— is provided 90 with a tubular extension —66— interiorly threaded to receive the threaded connection —67— of a valved-outlet —68— by means of which the hopper and sub-hopper may be emptied of their contents. Extending 95 around the upper edge of the hopper —50— is arranged a launder or trough-like member —69— which is secured, at one side, flush with the edge of the hopper, as at —70—, and at its other or forward side to, 100 but below, the edge of the hopper, by means of an apron —71—, which may or may not be continuous with the inner wall of the launder. A suitable discharge —72— is provided 105 for the drainage of the launder. 110

It is to be understood, however, that the launder —69— may be extended around a portion of the circumference of the hopper, in the one instance, or along only one or more of the sides of the same, in the other 115 instance, in which case that portion of the hopper not engaged by, or formed with, the launder, would be extended sufficiently above that side or sides of the hopper, engaged by the launder, so as to prevent an over-flow of 120 material therefrom.

In Fig. 8, of the drawing, there is shown a modified form of the agitator casing, designated —73—, which may be made square, as shown, instead of a cylindrical formation, 130

as hereinbefore described, and the same may be used in connection with either the frusto-conical or the frusto-pyramidal shaped hoppers.

- 5 In the operation of the preferred form of the invention, after power has been applied to the pulley 38, the pulp, consisting of the crushed or pulverized ore, suitable chemicals, and an oil or other selective liquid, is introduced through the feed-hopper 44 into the agitator casing 12, and onto the first baffle-plate, whence, it flows or drops to the first agitator-disk, and is then thrown outwardly therefrom, by the centrifugal action 10 of the latter, against the wall of the casing and onto the succeeding baffle-plate. This action is repeated, throughout the several baffle-plates and agitator-disks, until the bottom of the casing is reached, where, by reason 15 of the inclined ribs 41 and the centrifugal action of agitator-disk provided with the same, the pulp is thrown outwardly through the openings 42 and into the upper portion of the hopper 1, which forms the separating chamber of the apparatus.

The thorough agitation of the pulp, during its passage through the agitator casing and its subsequent discharge into the separating chamber, causes a separation or concentration of the minerals or metals from the sand or tails, and the former, due to less weighty formation, is floated or frothed over the edge of the hopper 1 and into the launder 8, while the latter falls through the openings 23 to the sub-hopper chamber. By reason of the inclination of the launder 8, the concentrates readily flow to the discharge outlet 10 and into the discharge pipe 11. The tailings are discharged, when desired, through the valved-outlet 5, as a waste material, or the outlet 5 may be connected, in any suitable manner, not shown, to a second apparatus 40 for further treatment.

In the operation of the modified form of the invention, the pulp is to be introduced, through the feed-hopper 57, into the casing 53, simultaneously with the application of air, under pressure, through the pipe 61 to the nozzles 63. Thor-

ough agitation of the pulp continues until the hopper 50 fills, at which time, as in the first instance, the concentrates float or froth over the edge of the hopper 50 55 and into the launder 69, while the tailings fall through the openings 64 into the sub-hopper 51, to be discharged therefrom, when desired, in the manner hereinbefore described. The mineral or metal bearing froth flows from the launder 69, and is conveyed therefrom to a concentrate storage, not shown.

It is to be understood, however, that various modifications of the construction set forth herein, and that suitable drive mechanism for the operation of the machine, may be resorted to, without departing from the spirit of the invention.

Having thus fully described the invention, 70 what is claimed, is:—

An apparatus for separating minerals from their ores comprising a hopper, a casing disposed within and centrally of said hopper, said casing being provided with discharge openings arranged slightly above the plane of its bottom wall, spaced baffle-plates within said casing and provided with centrally alined openings, a cover-plate for the casing, bearings carried by the cover-plate, 75 a shaft depending from said bearings, agitator-disks carried by said shaft and operating between said baffle-plates, deflecting ribs formed on the under face of the lowermost of said agitator-disks, a feed-hopper carried 80 by said cover and opening into said casing, a supporting flange connecting said casing and the inner wall of said hopper and provided with inlet openings communicating the lower portion of the hopper and disposed below the bottom wall of the casing, a 85 valved-outlet arranged at the bottom of said hopper, and a launder surrounding the upper edge of the hopper and inclined with respect thereto.

In testimony whereof I affix my signature, in presence of two witnesses.

RAY P. SAFFOLD.
